(57) **CLAIM**

The ornamental design for display screen or portion thereof with a computer generated graphical user interface for placement of a medical tube or line as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view display screen or portion thereof with a computer generated graphical user interface for placement of a medical tube or line as shown and described showing an embodiment of our new design;

FIG. 2 is a front view of a second embodiment thereof; FIG. 3 is a front view of a third embodiment thereof; and, FIG. 4 is a front view of a fourth embodiment thereof. The broken line showing of the display screen or portion thereof forms no part of the claimed design. The broken lines showing portions of the graphical user interface form no part of the claimed design. The solid black, and grayscale images form no part of the claimed design.
